JEHYLEMAN SHAW, OF BRIDGEPORT, CONNECTICUT.

Letters Patent No. 65,287, dated May 28, 1867.

IMPROVED LIFE-PRESERVER.

The Schedule referred to in these Letters Patent and making part of the same.

TO ALL WHOM IT MAY CONCERN:

Be it known that I, J. SHAW, of Bridgeport, in the county of Fairfield, and State of Connecticut, have invented new and useful improvements in Life-Preservers, and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

The present invention consists in combining with the ordinary life-preservers, or those which are constructed to encircle and to be applied to the body of the person, one or more receptacles adapted to the reception and holding of water and food for the sustenance of life while the person wearing such preservers is afloat or in the water; these receptacles being constructed in such manner that the water in the one can be drunk without admitting the surrounding water, and the food in the other can be similarly removed for being eaten. In the accompanying plate of drawings my improvements in life-preservers are illustrated—

Figure 1 being a plan or top view of the same.

Figure 2, a section, taken in the plane of the line $x-x$, fig. 1.

Figure 3, a view showing the preserver upon a person's body.

Similar letters of reference indicate like parts.

A in the drawings represents a life-preserver of the ordinary and common form, suitable for being applied to the body of a person, straps B and buckles C being provided for such purpose. D and E, two receptacles or boxes attached to preserver A, one at each end, each of which receptacles is to be made in any suitable manner to be water-tight. One, D, of these receptacles is for the reception of water, or other liquid suitable for drinking purposes, and for drinking the same therefrom a tube, F, is provided, with a suitable mouth-piece and stopper, and an air-tube, G, for the admission of air to the interior of the receptacle, the drinking-tube extending to the bottom of the water receptacle, so as to enable the water to be entirely removed therefrom. The other receptacle, E, is for food, and for the insertion and removal of the same therefrom, an opening, H, is made in the upper end, for which opening a stopper or plug, I, is provided to stop the same. J, a flexible or elastic bag, secured to food receptacle at the end where the food is to be removed, which bag, at its mouth, is provided with an elastic, or other means suitable to cause it to tightly grasp and enclose about the hand as it is inserted therein to reach the stopper of the receptacle for removing it, whereby, as is obvious, the entrance of the water surrounding the life-preserver and its food receptacle is entirely prevented while the food is being removed, an advantage of the utmost importance. K, a stopper for the mouth of the flexible bag J, which stopper, as well as all the other stoppers used about the life-preserver embraced in the present invention, is to be attached to the same, so that whether in or out of place it cannot be lost.

Having thus described my invention, I claim as new, and desire to secure by Letters Patent—

The life-preserver, constructed as described, consisting of the water and food receptacles D E attached to the portion A, the water receptacle D provided with the air-tube G and drinking-tube F, the food receptacle provided with the opening H, closed with the plug I and the elastic bag J, substantially as described for the purpose specified.
